Fig. 1 is a top plan view of an expandable link chain for a bracelet embodying my new design with the links in contracted position;

Fig. 2 is a view similar to Fig. 1 with the links in an expanded position, portions of the conventional appearing bottom links being visible between the expanded top links;

Fig. 3 is an enlarged top plan view of a single top link of the expandable chain; and

Fig. 4 is an edge elevational view looking from right to left at the top link shown in Fig. 3.

The essential features of my design reside in the portions shown in full line.

I claim:

The ornamental design for an expandable link chain for a bracelet or similar article, substantially as shown and described.
